UNITED STATES PATENT OFFICE

2,580,101

SEWING MACHINE WORK-HOLDING ATTACHMENT FOR DARNING AND EM-BROIDERING

Ralph E. Johnson, Rahway, N. J., assignor to The Singer Manufacturing Company, Elizabeth, N. J., a corporation of New Jersey

Application January 15, 1948, Serial No. 2,456

5 Claims. (Cl. 112—121)

1

This invention relates to darning attachments for use with sewing machines, and more particularly to an attachment for holding the work suitably for darning and to facilitate maneuvering the work beneath the sewing needle.

Securing the work preparatory to performing darning operations thereupon may be accomplished by the use of nested clamping rings or darning hoops. To assist in disposing one clamping ring against the under surface of the work, it is a known expedient to mount the ring on the bed of the sewing machine. It is then possible to pull the work over the bed of the sewing machine and over the clamping ring in a single operation, the second clamping ring then being introduced from above in the usual manner.

Mounting a clamping ring upon the bed of the sewing machine, however, ordinarily results in restricting the freedom of movement of the ring and, consequently, the freedom of movement of the work clamped thereby. It is one object of this invention to provide a work-clamping attachment which may be mounted on the bed of a sewing machine, but which nevertheless possesses complete freedom of movement within defined limits. More specifically, this invention includes a new construction for a darning attachment or the like in which at least one of the clamping elements is mounted on the bed of the machine to simplify positioning and clamping the work, but which may be freely shifted beneath the needle to facilitate the execution of darns of any desired pattern.

It is a further object of this invention to provide work-clamping elements which may be easily engaged and disengaged, and which tension and position the work suitably for darning.

The invention also provides a work-clamping element having an annular gripping surface by means of which the operator may manipulate the attachment without touching the fabric. This is particularly effective in preventing soiling of the work and inadvertent interference with the tensioning thereof.

A detailed description of one embodiment of the invention, from which these and other advantages will be more clearly understood, follows in the specification referring to the drawings, in which:

Fig. 1 is a side elevational view of a portion of a cylinder-bed sewing machine showing the darning attachment mounted on the bed, and showing in cutaway section the means for mounting the attachment thereupon.

Fig. 2 is a top plan view of the cylindrical bed

2

of the sewing machine, including the mounted darning attachment, and with the needle and presser-bars sectioned along the line 2—2 of Fig. 1. Shown in broken lines are four of the extreme operating positions into which the darning attachment may be shifted.

Fig. 3 is an enlarged sectional view of the darning attachment taken substantially along the line 3—3 of Fig. 2 with the addition of a piece of work shown secured by the clamping elements.

Fig. 4 is an exploded perspective view of the component elements of the darning attachment.

The sewing machine, a portion of which is shown in the accompanying drawings, is of the cylinder-bed type having an eye-pointed needle 10 carried by a reciprocating needle-bar 11. The sewing machine is provided with a substantially cylindrical bed-portion 12 having a flattened upper or working surface and housing a feed-dog 13 along with the usual feed-dog actuating and loop-seizing mechanism. A detailed illustration of such a machine may be observed by reference to U. S. Patent No. 2,386,660 of A. B. Clayton.

Also contained within the bed is a mechanism for lowering the feed-dog beneath the plane of the throat-plate 14 to prevent its interference with the freedom of movement of the work required in performing darning operations. A typical device of this type is shown in the U. S. Patent No. 1,908,292 of A. Grieb.

A darning presser-foot 15 is secured to a presser-bar 16. In order to provide for freedom of movement of the work, it is also helpful to cyclically raise the presser-foot from engagement therewith. This temporary disengagement occurs once in each stitch-forming cycle immediately following the time of seizure of the needle-thread by the loop-taker, and may be accomplished by any one of several commonly used devices, one of which is shown in the U. S. Patent No. 2,009,194 of P. Hleb.

The darning attachment comprises an annular bearing ring or supporting element 17 (Fig. 4) carried by one end of a supporting arm or element 18 provided with a longitudinal slot 19. A mounting pin 20, slidably but non-rotatably mounted in the slot 19, is provided on its depending end with a head or lug 21 by means of which the pin may be anchored in the bed of the sewing machine. This is accomplished by introducing the rectangular lug 21 into a correspondingly shaped slot 22 in a bed-plate 23. The lug underlies the under surface of the bed-plate thus permitting the pin to pivot about its cylindrical shank portion 24. In the normal operating po-

sitions of the attachment the long axis of the lug 21 is disposed transversely to that of the slot 22, thus preventing accidental withdrawal of the pin.

A clamping element 25 provided with a split 25', and having as its cross-section an outwardly opening channel including a cylindrical wall in the form of a ring 26 and circumferential flanges 27 and 32, is sprung within the bearing ring 17. The bearing ring 17, its supporting arm 18, and the split clamping element 25 form a unitary structure, the respective components of which are not separable in normal use. It is to be noted, however, that the clamping element 25 may be rotated relatively to the bearing ring 17.

A second clamping element 28 cooperates with the clamping element 25 to secure the work W, as illustrated in Fig. 3. The clamping element 28 is comprised of an annular shelf or flange 29 from which depend the concentric cylindrical rings 30 and 31. When the clamping elements are in engagement, these cylindrical rings embrace the flange 27 of the element 25.

To operate the device the work is placed over the clamping element 25 with the damaged fibers disposed centrally thereof, and the clamping element 28 is pressed downwardly onto the element 25. The latter is forced to yield radially inwardly by the rigid outer cylindrical ring 30 of the clamping element 28, and the work is consequently gripped between the outer edge of the upper horizontal flange 27 and the inner face of the cylindrical ring 30. The inner ring 31 is wider than the outer ring 30 so that in work-clamping position, the lower rim of the ring 31 is approximately at the level of the lower face of the supporting arm 18, thereby causing the work to be disposed substantially in the plane of the throat-plate 14. As the clamping elements are pressed into engagement, the inner ring 31 of the element 28 causes the work to be drawn taut by an amount proportional to the clamping force of the aforementioned clamping surfaces. This clamping force is supplemented by the snubbing action of the fabric about the lower edges of the cylindrical rings 30 and 31, as well as about the inner edge of the flange 27.

In engaging the clamping elements, the cylindrical ring 31 of the clamping element 28 fits loosely within the element 25 and acts as a piloting or positioning member which centers the clamping elements prior to the time that they are pressed into engagement. It should also be noted that the horizontal shelf 29 of the clamping element 28 overlies the element 25 and thus forms a surface by means of which the attachment may be held by the operator in maneuvering the work beneath the needle.

The pair of engaged clamping elements 25 and 28 may be rotated as a unit relatively to the bearing ring 17. The bearing ring 17, on the other hand, may be turned about the pivot pin 20, and in addition, may be shifted linearly within the limits defined by the length of the slot 19 in the supporting arm 18. This combination of motions available to the work clamping elements enables the work secured thereby to be shifted with complete freedom in a horizontal plane within the defined limits.

Having described in detail an apparatus considered to represent a typical embodiment of the invention, what is claimed is:

1. A work-holding device of the class described comprising: a first clamping element, a second

clamping element including a pair of concentric cylindrical rings, and a shelf joining said cylindrical rings, said clamping elements being adaptable to be pressed into concentric engagement in which the first clamping element is disposed radially within the concentric rings of the second clamping element.

2. A work-holding device of the class described comprising: a first clamping element including a cylindrical ring, and a flange extending outwardly therefrom, a second clamping element including a pair of concentrically disposed cylindrical rings, and a shelf joining the rings, said first and second clamping elements being adaptable to be pressed into substantially concentric engagement in which the first clamping element is disposed within the radial confines of the pair of cylindrical rings of the said second clamping element.

3. A work-holding device of the class described comprising: a first annular clamping element the cross-section of which is an outwardly opening channel, a second annular clamping element the cross-section of which is a downwardly opening channel, said clamping elements being adapted to be pressed into concentric engagement in which the first clamping element is at least partially disposed within the channel of the second clamping element.

4. A work-holding device for use with a sewing machine comprising: a first annular clamping element the cross-section of which is an outwardly opening channel, a second annular work-clamping element the cross-section of which is a downwardly opening channel, said second clamping element being adaptable to engage said first clamping element, an annular supporting element journaled within the channel of the said first clamping element, said clamping elements being rotatable relatively to said supporting element, and a supporting arm carrying said supporting element adaptable to be removably mounted on a sewing machine.

5. A work-holding device for use with a sewing machine comprising: a first annular clamping element the cross-section of which is an outwardly opening channel, a second annular work-clamping element the cross-section of which is a downwardly opening channel, said second clamping element being adaptable to engage said first clamping element, an annular supporting ring journaled within the channel of the first clamping element, said clamping elements being rotatable relatively to said supporting ring, a slotted supporting arm affixed to said supporting ring, and a pin slidably mounted in said slotted supporting arm by means of which the device may be mounted upon a sewing machine.
